US00D756394S

(12) **United States Design Patent**
Kim et al.

(10) **Patent No.:** US D756,394 S
(45) **Date of Patent:** ** May 17, 2016

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Yusic Kim**, Suwon-si (KR); **Jungah Seung**, Guri-si (KR); **Donghoon Sohn**, Seoul (KR)

(73) Assignee: **SAMSUNG ELECTRONICS CO., LTD.**, Suwon-Si (KR)

(**) Term: **14 Years**

(21) Appl. No.: **29/507,333**

(22) Filed: **Oct. 27, 2014**

(30) **Foreign Application Priority Data**

Aug. 25, 2014 (KR) 30-2014-0041213

(51) **LOC (10) Cl.** **14-04**

(52) **U.S. Cl.**

CLAIM

The ornamental design for a display screen or portion thereof with graphical user interface, as shown and described.

DESCRIPTION

The FIGURE is a front view of a display screen or portion thereof with graphical user interface showing our new design. The broken line showing of the text within the FIGURE represent portions of the graphical user interface that form no part of the claimed design.

The broken line around the FIGURE shows the display screen or portion thereof and forms no part of the claimed design.

1 Claim, 1 Drawing Sheet
